FIG. 2

FIG. 3

FIG. 1 is a front elevational view of a building, showing my new design;

FIG. 2 is a top plan view; and

FIG. 3 is a horizontal sectional view on the line 3—3 of FIG. 1.

The rear of the building is essentially the same as the front shown in FIG. 1 except that the walls showing the entrance are plain.

I claim:

The ornamental design for a building, as shown and described.
